OF KENOSHA, WISCONSIN, A CORPORATION OF DELAWARE.

METAL TABLE.

Application filed August 13, 1923 Serial No. 657,068.

My invention relates to improvements in metal tables in general, and has particular reference to a means of reinforcing a relatively thin metallic face sheet to prevent same from buckling while substantially eliminating the metallic sound.

The principal objects of the invention are to provide an improved reinforcing means of the character described; to provide an improved deadening means for substantially eliminating the metallic clang which is ordinarily associated with thin metal sheets; to provide an improved construction of the character described which may be adapted to sheets or surfaces of any area within the desired requirements; to provide a reinforcing and deadening means which, when applied to the sheet will not impair the original level surface thereof but which will, on the contrary, tend to eliminate waves or buckles present therein; to provide an improved combined frame work and reinforcing means for a metal face sheet which, when applied to the sheet renders the latter capable of being handled as a rigid self-sustaining table member; to provide a construction particularly adapted to be made of metallic tubing throughout, thereby securing maximum lightness and also economy of metal; to provide a construction which shall be simple and inexpensive in design and to manufacture and in general to provide, a neat, rigid, rugged and efficient construction of the character referred to.

Referring to the drawings accompanying this application which show my invention as applied to a table suitable for use as a top for a bedroom dresser or other article of furniture,

Fig. 1 is an under side perspective view of the table.

Fig. 2 is a section taken on the line 2—2 of Fig. 1.

Fig. 3 is a section taken on the line 3—3 of Fig. 1.

Fig. 4 is a section taken on the line 4—4 of Fig. 1, and

Fig. 5 is an enlargement of a portion of Fig. 2.

Throughout the specification, the word table is used in its broadest sense as including any sheet or supporting surface with or without legs or other sustaining means of support.

Referring to the drawings, 10 represents

the face sheet which is constructed of relatively thin metal, preferably previously flattened or leveled in any suitable device such as what is known in the trade as a "patent leveling machine". Said sheet, as to its outer margins, is supported upon an underlying rectangular frame constructed throughout of rectangular tubing preferably steel, of comparatively light gauge, so as to provide the maximum rigidity with minimum of metal. Said rectangular frame comprises a pair of side bars 11 and 12 which extend the full length of the face sheet, and a pair of end bars or cross pieces 13 and 14 which are respectively interposed between the adjacent ends of the pair of longitudinals 11 and 12. The cross pieces and side pieces 11 and 12 are secured together in any suitable manner, although in the present instance I have shown the corner joints formed by acetylene welding, as indicated at 15 and 16.

Said rectangular border frame may be made up in advance if desired, and slid into position under the top or face sheet 10, the side and end margins of which latter are flanged over as indicated at 17 and 18 in order to hold said sheet margin and border frame securely together. The edge of said flange 18 is permanently secured in position by means of fusible bonds as at 19 of soft or hard solder, but before doing so the marginal deadening strips are inserted. Said deadening strips 20, both as to those at the margins and the intermediate ones, which will later be described, may be made of some suitable fibrous porous and more or less flexible material such as cardboard and are interposed between the under side of the face sheet 10 and the upper surfaces of the members of the rectangular border frame.

The margins of the sheet 10 are preferably so flanged as to provide a snug fit for the deadening strips 20 and in order still further to secure such strips in position against sliding inwardly, I prefer to connect the upper inner edge of the border frame 21 to the adjacent under surface of the face sheet 10 by means of drops or localized applications of solder as indicated at 22. Said bonds 22 not only prevent displacement of the deadening strips 20, but also hold down the marginal portions of the top sheet 10 securely in contact with said deadening strips 20. Hence rattling or vibration of the side portions of the face sheet 10 is prevented and

the danger of said surface portions buckling upwardly is eliminated.

Where the table is of comparatively limited dimensions, or where conditions permit of 5 a fairly heavy top sheet, intermediate reinforcing members may not be essential but in the ordinary case it is found desirable to apply intermediate reinforcing members spaced to suit the requirements of the particular top. In this instance I have indicated a series of three similarly constructed and similarly spaced reinforcing or stiffening members. Each of said reinforcing members 23 comprises a length of rectangular 10 light weight tubing preferably running from end to end of the table parallel with the side pieces 11 and 12 and underlying the face sheet 10 in the same manner as the members of the rectangular border frame. 15 Each of said members 23 is secured at its ends to the cross pieces 13 and 14 respectively by any suitable means such as brazing or welding, and, like the members of the rectangular border frame, is suitably spaced 20 below the plane of the sheet 10 in order to permit the insertion of a deadening strip 24 similar in character to the deadening strip 20. Said intermediate reinforcing bars 23 also have their edges fusibly united or bonded 25 to the under surface of the sheet 10 by means of drops or localized applications of soft solder as at 25 and 26, which bonds also serve to hold the deadening strip in position. I prefer to use soft solder for uniting the 30 edges of the face reinforcing members to the under side of the sheet 10 for the reason that when using soft solder, there is less danger of burning the deadening material and, furthermore, which is more important, on account of the much lower temperature, there 35 is no danger of injuring the level surface of the face sheet by overheating.

The described details of construction and operation are merely illustrative of a single 40 application of my invention, the scope of which should be determined by reference to the appended claims, said claims being construed as broadly as possible consistent with the state of the art.

50 I claim as my invention:

1. In a table, the combination of a metallic face sheet, a reinforcing frame member underlying said sheet, a deadening member interposed between said sheet and frame member, and means on the under side of said face sheet for uniting together said sheet and frame member beyond the edge of said dead-

ening member to prevent separation of the sheet and frame member, and also to prevent sidewise displacement of said deadening member. 60

2. In a table, the combination of a metallic face sheet, a substantially rigid reinforcing bar underlying said sheet, a deadening strip of substantially the same width as that of said reinforcing bar interposed between said sheet and bar, and means for uniting together said sheet and bar beyond the edge of said strip to prevent separation. 65

3. In a table, the combination of an imperforate metallic face sheet, a substantially rigid metal reinforcing bar underlying said sheet, a deadening strip interposed between said sheet and bar, and means for uniting together said sheet and bar beyond the edge 70 of said strip to prevent separation thereof, and also to prevent sidewise displacement of said deadening strip.

4. In a metallic table, the combination of a thin imperforate metallic face sheet, a hollow metal reinforcing bar underlying said sheet, a strip of deadening material interposed between said sheet and bar, and means for uniting together said sheet and bar comprising fused metal bonds at opposite edges 80 of said bar, said bonds being effective to prevent separation thereof. 85

5. In a table, the combination of an imperforate metallic face sheet, a hollow metal reinforcing bar underlying said sheet and 90 having a pair of coplanar spaced edges adjacent said sheet, a strip of deadening material interposed between said sheet and said bar, and means for uniting together said sheet and bar to prevent separation thereof and to clamp said deadening strip therebetween comprising spaced localized fused metal bonds connecting the under side of the sheet to points along an edge of the bar. 95

6. In a table, the combination of a metallic face sheet and a metallic frame, said frame comprising peripheral members and a reinforcing bar extending from one of the peripheral members to another, said face sheet being disposed over said frame, and 100 deadening strips interposed between the frame members and the face sheet, said face sheet being held in place over said frame members by means of fusible metal bonds 105 extending from the frame members to the face sheet, said bonds also serving to hold 110 said deadening strips in place.

CORNELIUS C. O'CONOR.
